UNITED STATES PATENT OFFICE.

WILLIAM E. WEBB, OF LARCHMONT, NEW YORK.

NECKWEAR.

Application filed August 16, 1927. Serial No. 213,367.

This invention relates to neckwear and more particularly to ties of the four-in-hand type. Such ties are commonly made of fabric so cut and folded along longitudinal lines 5 as to provide front and back folds forming a neck-band portion and enlarged tying ends. The opposed edges of the back fold are stitched together to form a seam which extends throughout the greater portion of 10 the length of the tie.

An object of the present invention is to provide a tie having a longitudinally and transversely resilient body portion; a longitudinally and transversely resilient lining, 15 and a longitudinally and transversely resilient reinforcing strip secured to the back side of the body portion of the tie. This reinforcing strip is arranged to overlie and protect the back seam of the tie for the 20 greater portion of the seam length.

By forming the tie in this manner its entire structure is rendered longitudinally and transversely resilient so that when the tie is relieved of a pulling strain which distorts it, 25 it will resume its original flat shape and dimensions. The structure is adapted to provide a tie of great durability without sacrificing the very desirable feature of resilience, which greatly facilitates the tying of a well- 30 shaped knot and holds the knot properly positioned upon the collar. The reinforcing strip protects the back seam without materially reducing the longitudinal elasticity of the tie as a whole.

35 A further object of the invention is to generally improve the structure of a necktie.

In the drawings:

Fig. 1 is a view of the face or outer side 40 of my improved necktie;

Fig. 2 is a view of the back or inner side of the tie;

Fig. 3 is a view similar to Fig. 2 with parts broken away;

Fig. 4 an enlarged transverse section taken 45 on the line 4—4 of Figs. 1 and 3; and

Fig. 5 an enlarged transverse section taken on the line 5—5 of Figs. 1 and 3.

Referring to the various parts by numerals 50 1 designates the tubular body of the necktie, the fabric of which is cut and folded to form a longitudinal seam 2 along the center of the inner or back side thereof, said seam being formed by tight machine stitching. This seam is preferably arranged along the center line of the tie. The main body of the tie is cut so that the threads thereof are on

the bias, or oblique to the longitudinal line of the tie so that said body will be more or less elastic or resilient longitudinally and transversely. The tie is provided with a lining 4 which extends throughout the neckband portion and the knot forming portions of the tie. This lining is formed of suitable woven material cut or woven so that its threads run on the bias with relation to the longitudinal line of the tie. It is preferably formed of tightly woven threads and is somewhat heavier and stronger than the exterior body part of the necktie, so that it will have a greater transverse resilience than 70 the body of the tie.

The material of the tie is so cut and folded that a long narrow neckband portion 3 and two knot-forming portions 9 and 9^a are formed, the extreme ends 5 being open and 75 considerably enlarged, as is usual in this type of neckwear. In order to reinforce the longitudinal seam 2 an inner reinforcing strip 6 is secured along the seam by the machine stitching 7 thereof. The reinforcing strip 80 6 is formed of suitable woven material cut or woven so that its threads run on the bias with relation to the longitudinal line of the tie, in order to make it longitudinally and transversely resilient.

85 The neckband and those portions of the body of the tie immediately adjacent thereto which constitutes the knot-forming portions of the tie, receive the greatest wear and the greatest pulling strain. To reinforce and 90 protect this part of the tie I secure to the inner side or back thereof a long outer reinforcing elastic or resilient band 8. This band extends over both the neckband portion 3 and the knot-forming portions 9 and 9^a of 95 the tie. Its width is nearly equal to that of the neckband portion. The portion of the band overlying the neckband portion and the smaller tying end 9^a is secured by tight machine stitches 10 along its longitudinal 100 edges. These stitches pass through both the front or face fold and the back fold of the neckband portion and the smaller tying end, and through the lining 4 so that the neckband portion and the smaller tying end are flat and 105 the neckband portion will slide freely between the folds of the collar. Transverse lines of machine stitches 11 also secure the band to the tie at two points in its length. The portion of the band overlying the larger knot-forming portion 9 of the tie is secured by 110 hand or loose stitches 12 along its longitudi-

nal edges, and by transverse loose stitches 11^a, which pass through only the back fold and the lining 4 of the tie. The longitudinal edges of the interlining 4 are free and 5 unstitched in the knot-forming portions of the tie.

The reinforcing band 8 is formed of woven fabric with its threads extending on the bias with relation to the longitudinal line of the tie in order to render the band longitudinally and transversely elastic or resilient. Thus 10 all of the superposed elements of the tie are longitudinally and transversely resilient, and the tie is freely stretchable throughout its entire length. The band 8 protects the rear seam from the head of the back collar button and said band is preferably made of substantial tape material in order to resist the wear as it is dragged over the collar button, when 15 adjusting the tie for the knot-forming operation. It will be seen that the tie structure combines the advantages of durability and resilience.

The neckband portion and the smaller end 20 portion 9^a of the tie will have less stretchability and resilience than the larger knot-forming portion 9 of the tie. The tight machine stitches 10 which connect the reinforcing piece to the back and face folds of the necktie proper will not only strengthen that portion 25 of the necktie but will render it slightly less elastic and stretchable. The band or loose stitches 12 which secure the reinforcing piece 8 to the back fold of the larger tying 30 end of the tie and to the lining 4 will only slightly reduce the free stretchability and resilience of the larger knot-forming portion of the tie. The wider flaring ends of the tie beyond the reinforced portion of the seam will 35 be soft and flexible and have the maximum stretchability and resilience. It is desirable that the neckband portion of the tie and the smaller end portion thereof have a certain degree of elasticity but this degree of elasticity need not be as great as the elasticity 40 and resilience of the larger knot-forming portion of the tie. The elasticity and resilience of the neckband portion and of the smaller end portion assists materially in holding the 45 necktie in its final adjusted position in a soft double-fold collar. The greater elasticity and resilience of the larger knot-forming portion assists materially in forming a knot of pleasing appearance and also is very important in returning the knot-forming portion 50 of the tie to its original smooth flat condition when the knot is untied and the necktie is not in use. The soft end portions of the tie give the tie a pleasing appearance and 55 maintains those portions always in flat un-ruffled condition.

The resilient reinforcing strip stitched on the back of the tie not only protects the back seam but increases the transverse resilience of 60 the tie and helps to flatten out both ends of

the tie as well as the neckband portion when the necktie is not in use. This overlying bias cut strip is attached to the back fold of the necktie by stitches running along its longitudinal edges. This reinforcing strip, because of its bias threads, flattens out transversely; and because its longitudinal edges are stitched to bias cut material the whole body of the tie flattens out, or remains flat. The stitching of the bias cut reinforcing 70 strip to the bias cut body and to the bias cut lining increases the tendency of the tie to flatten out when not in use, and increases the transverse resilience of the necktie. The lines of stitches along the longitudinal edges of the 75 reinforcing strip reduce the longitudinal stretchability of the tie but the resulting structure has a stronger tendency to flatten out when released from the knot than it would have if the reinforcing strip were not present. 80 85

While I have shown and described a four-in-hand tie, it will be understood that the novel structure is adaptable to ties of other types. I also do not wish to be limited to a tie whose elements are formed of woven fabric and derive their elasticity or resilience 90 from a bias arrangement of the threads. Certain of the elements, such as the outer reinforcing strip, may be formed of other material and derive their elasticity in other ways. 95

This application is a continuation in part of my application for patent for neckwear, filed on November 14, 1925, Serial No. 69,104.

What I claim is:

1. A longitudinally and transversely resilient necktie formed of folded fabric and comprising a narrow neckband portion, a larger knot-forming end portion and a smaller end portion, the edges of the folded fabric forming a longitudinal seam at the back of the tie, in combination with a flexible resilient longitudinally stretchable interlining extending throughout the neckband portion and substantially throughout the two end portions, and means to render said necktie 100 stretchable to a less degree in the neckband portion and the smaller end portion than in the knot-forming portion. 105

2. A longitudinally and transversely resilient necktie formed of folded fabric and comprising a narrow neckband portion, a larger knot-forming end portion and a smaller end portion, the edges of the folded fabric forming a longitudinal seam at the back of the tie, in combination with a flexible resilient 110 longitudinally stretchable interlining extending throughout the neckband portion and substantially throughout the two end portions, a longitudinally stretchable and resilient reinforcing piece covering said seam 115 throughout the entire length of the neckband and substantially throughout the length of the end portions of the necktie, and means for securing said reinforcing piece to the necktie 120 structure in such manner as to render the 125 130

neckband portion and the smaller end portion longitudinally stretchable to a less degree than the knot-forming portion of the necktie.

5. 3. A necktie formed of bias cut resilient fabric folded to form a narrow neckband portion and wider end portions, one of said end portions constituting a knot-forming portion, tight machine stitches securing the edges of 10 the folded fabric to form a longitudinally extending seam at the back of the tie, an interlining extending throughout the neckband portion and substantially throughout the two end portions of the necktie said lining being formed of bias cut longitudinally and 15 transversely resilient material, a longitudinally and transversely resilient reinforcing piece covering the said seam throughout the entire length of the neckband portion and 20 substantially throughout the length of the end portions of the necktie, tight machine stitches securing the reinforcing piece along its longitudinal edges at opposite sides of the seam to the back and face folds of the tie in 25 the neckband portion and one end portion, said stitches passing through the interlining, loose hand stitches securing the said reinforcing piece along its longitudinal edges at opposite sides of the seam to the back fold of 30 the necktie fabric and to the enclosed resilient lining in the knot-forming portion of the tie, the longitudinal edges of the interlining being free beyond the ends of the seam in 35 the necktie fabric, whereby the necktie structure will have different degrees of stretchability and resilience at different points in its length.

4. A necktie formed of bias cut resilient fabric folded to form a narrow neckband portion and wider end portions, one of said end portions constituting a knot-forming portion, tight stitches securing the edges of the folded fabric to form a longitudinally extending seam at the back of the tie, an interlining extending throughout the neckband portion and substantially throughout the two end portions of the necktie said lining being formed of bias cut longitudinally and 45 transversely resilient material, a longitudinally and transversely resilient reinforcing piece covering the said seam throughout the entire length of the neckband portion and substantially throughout the length of the end portions of the necktie, tight stitches securing the reinforcing piece to the back and 50 face folds of the tie in the neckband portion said stitches passing through the interlining, and loose stitches securing the said reinforcing piece to the back fold of the necktie fabric and to the enclosed resilient lining in the 55 knot-forming portion of the tie.

5. A longitudinally and transversely resilient necktie having an outer body formed of bias cut folded fabric and comprising a narrow neckband portion, a larger knot-forming

end portion and a smaller end portion, the edges of the folded outer fabric forming a longitudinal seam at the back of the tie, in combination with a flexible longitudinally and transversely resilient stretchable interlining extending throughout the neckband portion and substantially throughout the two end portions said interlining being bias cut fabric heavier and stronger than the exterior body part of the necktie and formed of tightly woven threads whereby it will have a greater longitudinal and transverse resilience than the outer body of the tie, and means to render said necktie longitudinally stretchable to a less degree in the neckband portion 70 and the smaller end portion than in the larger knot-forming portion.

6. A longitudinally and transversely resilient necktie having an outer body formed of bias cut folded fabric and comprising a narrow neckband portion, a larger knot-forming end portion and a smaller end portion, the edges of the folded outer fabric forming a longitudinal seam at the back of the tie, in combination with a flexible longitudinally and transversely resilient stretchable interlining extending throughout the neckband portion and substantially throughout the two end portions, said interlining being formed of bias cut fabric heavier and stronger than the exterior body part of the necktie and formed of tightly woven threads whereby it will have a greater longitudinal and transverse resilience than the outer body 85 of the tie, a longitudinally and transversely resilient and stretchable exterior reinforcing piece having a width substantially equal to that of the neckband portion and disposed on the back of the tie to cover the seam along the neckband portion and the knot-forming 90 portions of the tying ends, and rows of stitches securing said reinforcing piece to the tie body along the longitudinal edges of said piece in such manner as to render the neckband portion and the smaller end portion 95 longitudinally stretchable to a less degree than the larger knot-forming portion.

7. A necktie formed of bias cut resilient fabric folded to form a body including a neckband portion, tying ends, and a longitudinal seam at the back of the tie, and interlining extending through the knot-forming portion of one of said tying ends and formed of bias cut resilient fabric, an exterior reinforcing band at the back of the tie body over said seam formed of bias cut resilient fabric and extending along the neckband portion and the tying ends, loose stitches securing the longitudinal edges of said reinforcing strip to the tie body along said knot-forming 115 portion and also to the enclosed interlining, and tight stitches securing the longitudinal edges of the band to the tie body along the neckband portion and the other tying end.

8. A longitudinally and transversely re-

silient necktie having an outer body formed of bias cut folded fabric and comprising a narrow neckband portion, a large knot-forming end portion and a smaller end portion, the edges of the folded outer fabric forming a longitudinal seam at the back of the tie, in combination with a flexible longitudinally and transversely resilient stretchable interlining extending throughout the neckband portion and substantially throughout the two end portions, said interlining being formed of bias cut fabric heavier and stronger than the exterior body part of the necktie and formed of tightly woven threads whereby it will have a greater longitudinal and transverse resilience than the outer body of the tie, an exterior reinforcing piece having a width substantially equal to that of the neckband portion and disposed on the back of the tie to cover the seam along the neckband portion and the smaller tying end, and rows of stitches securing said reinforcing piece to the tie body along the longitudinal edges of said piece.

9. A necktie comprising a longitudinally and transversely stretchable and resilient fabric body including a neckband portion and tying ends, an exterior reinforcing band at the back of the tie body formed of material stretchable and resilient longitudinally and transversely of the tie and extending along the neckband portion and the tying ends, tight stitches extending along the longitudinal edges of said band and securing it to the tie body along the neckband portion and one of the tying ends, and loose stitches extending along the longitudinal edges of the band and securing it to the tie body along the other tying end.

10. A neckband formed of bias cut resilient

fabric folded to form a body including a neckband portion, tying ends and a longitudinal seam at the back of the tie, an exterior reinforcing band having a width substantially equal to that of the neckband portion 45 and disposed at the back of the tie body over said seam and formed of bias cut fabric extending along the neckband portion and the knot-forming portion of one of the tying ends, rows of tight stitches securing the reinforcing band along its longitudinal edges to the neckband portion at opposite sides of the seam, and rows of loose stitches securing said band along its longitudinal edges to said knot-forming portion at opposite sides 55 of the seam.

11. A longitudinally and transversely resilient necktie having an outer body formed of bias cut folded fabric and comprising a narrow neckband portion, a larger knot-forming end portion and a smaller end portion, the edges of the folded outer fabric forming a longitudinal seam at the back of the tie, in combination with a flexible longitudinally and transversely resilient stretchable interlining extending throughout the neckband portion and substantially throughout the two end portions, said interlining being bias cut fabric heavier and stronger than the exterior body part of the necktie 70 and formed of tightly woven threads whereby it will have a greater longitudinal and transverse resilience than the outer body of the tie, and means to render said necktie longitudinally stretchable to a less degree in 75 the neckband portion than in the larger knot-forming portion.

In testimony whereof I hereunto affix my signature.

WILLIAM E. WEBB.
